UNITED STATES PATENT OFFICE.

JAMES F. DAVIS, OF SAG HARBOR, NEW YORK.

REFRIGERATOR-GUARD.

No. 875,785.

Specification of Letters Patent.

Patented Jan. 7, 1908.

Application filed May 20, 1907. Serial No. 374,701.

To all whom it may concern:

Be it known that I, JAMES F. DAVIS, a citizen of the United States, residing at Sag Harbor, in the county of Suffolk and State of New York, have invented a new and useful Refrigerator-Guard, of which the following is a specification.

This invention relates generally to refrigerators, and more particularly to a novel form of guard or shield therefor.

The object of the invention is in a ready and practical manner to prevent damage to the refrigerator casing due to blows received therefrom by ice in being placed in the refrigerator, and also, in a similar manner to protect the door sill from like injury.

With the above and other objects in view as will appear as the nature of the invention is better understood, the same consists, generally stated, in a guard for refrigerators embodying a metallic body portion, constituting a casing shield having a facing of any suitable textile material, such as heavy flannel, felt or the like, and a cleat or extension constituting a door sill shield, and embodying a keeper to engage with the inner side of the sill of the door opening to hold the guard in position and also to protect such part from injury. The casing and sill shields may be constructed of any suitable material, preferably of galvanized iron, and to the sill shield is firmly secured a batten to rest upon the sill, the batten being in general construction formed to correspond with the sill, thereby to assist in causing the union between the guard and the refrigerator to be of a stable character.

The invention consists further in the various novel details of construction of a guard for a refrigerator as will be hereinafter fully described and claimed.

In the accompanying drawings, forming a part of this specification and in which like characters of reference indicate corresponding parts, -Figure 1 is a vertical sectional view through a portion of a refrigerator exhibiting the guard of the present invention applied thereto. Fig. 2 is a perspective detail view of the guard.

Referring to the drawings, C designates a portion of a refrigerator casing, S the door sill thereof and D a portion of the door. These parts may be of the usual or any preferred construction and, therefore, need no detail construction.

The present invention resides in a novel form of guard for shielding both the casing adjacent to the door and also the sill. This guard comprises a body portion 1, constituting the casing shield, which is made preferably of heavy galvanized iron, and has applied to its back or inner face a covering 2 of any suitable material, such as cloth, felt or the like, which serves effectually to prevent any bruising or marring of the refrigerator casing should the shield or body 1 be struck by a piece of ice that is being lifted towards the opening in the refrigerator.

The casing shield, as herein shown, is approximately trapezoidal in contour but this is not essential as it may be rectangular or of any other shape desired. The upper edge of the shield is bent approximately at right angles to its length to form a door sill shield 3, the free end or edge of which is bent to occupy a position approximately parallel with the casing shield to constitute a keeper 4 to hook over the inner edge of the sill thus to hold the guard securely in place, the horizontal portion of the shield 3 serving to protect the sill against injury. In order to prevent any yielding of the keeper due to the weight of the ice, or from blows, a batten 5 is assembled therewith, as by rivets or bolts 6, this batten being designed to bear upon the door sill, as clearly shown in Fig. 1, and thus secure the objects sought.

When the guard is in position, as shown in Fig. 1, not only will the front or side of the refrigerator casing adjacent to the door opening be thoroughly protected against injury, but the door sill will in a similar manner be shielded so that a close and intimate junction between the door and sill will always be secured.

Having thus described the invention, what is claimed is:—

1. A refrigerator guard comprising a cas-
